RELEASEABLE HANDLE FOR VESTIBULE CURTAINS

Filed March 11, 1927

Patented Jan. 3, 1928.

1,654,707

UNITED STATES PATENT OFFICE.

HARRY H. SCHROYER, OF CHICAGO, ILLINOIS, ASSIGNOR TO MORTON MANUFACTURING COMPANY, A CORPORATION OF ILLINOIS.

RELEASABLE HANDLE FOR VESTIBULE CURTAINS.

Application filed March 11, 1927. Serial No. 174,447.

In the use of vestibule curtains between the vestibules of railway coaches considerable difficulties are encountered when coaches are separated by having the handles 5 pulled off of the curtains or the handle and curtain pulled off of the curtain mounting due to the failure of the brakeman or other car attendant to release the curtain handle from engagement with its hook before the 10 coaches are separated.

To obviate the above conditions this invention has been devised for the purpose of providing an improved handle for use on a railway car vestibule curtain, said handle 15 being constructed with a bowed resilient handle section pivotally mounted at one end to a supporting section having notches or locking pockets therein permitting the second end of the bowed handle to be releasably 20 sprung into locking engagement with said notched supporting section under ordinary conditions but permitting the curtain handle section to be automatically released from engagement with a curtain handle hook on an 25 adjacent car when a pair of cars are separated and an attendant has failed to release the vestibule curtain.

It is an object of this invention to provide an improved releasable handle for a 30 railway car vestibule curtain said handle being so constructed that under normal conditions it will remain latched while under abnormal conditions or strains the handle will automatically release before permitting 35 injury thereto or to a vestibule curtain to which the handle is attached.

It is also an object of this invention to provide a railway car vestibule curtain with a handle mounting having a handle member 40 pivotally engaged thereon adapted to be held in a latched tensioned position under ordinary conditions of use but furthermore being adapted to permit release of the tension handle when subjected to abnormal tensional strains.

It is furthermore an object of this invention to provide an improved handle mechanism adapted for use on vestibule curtains and the like, said handle mechanism embracing a handle support having communicating recesses therein permitting a free end of a pivoted handle to be first engaged in one of said recesses and then moved into latching position with the other of said recesses to hold the handle tensioned in a latched posi-

tion ready for release under abnormal strains.

It is an important object of this invention to provide a vestibule curtain with an improved releasable handle which is adapted to 60 be engaged on a vestibule curtain hook and which will permit of automatic release from engagement with said hook when a pair of railway cars are separated prior to the disconnection of the curtain from engagement 65 with its hook.

Other and further important objects of this invention will be apparent from the disclosures in the drawings and specification.

The invention (in a preferred form) is 70 illustrated in the drawings and hereinafter more fully described.

On the drawings:

Figure 1 is a front plan view of an improved vestibule curtain releasable handle 75 mechanism in open position embodying the principles of this invention.

Figure 2 is a plan view of the releasable handle in closed position.

Figure 3 is a fragmentary detail view of 80 the handle showing the first step in the closing of the handle.

Figure 4 is a transverse sectional view taken on line 4-4 of Figure 1.

As shown on the drawings:

The improved releasable railway car vestibule curtain handle mechanism of this invention comprises a connecting bar 1 having integrally formed on one end thereof a split clamping sleeve 2 having apertured 90 clamping flanges 3 integrally formed on the split ends thereof. Also integrally formed on the clamping sleeve 2 is a notched or recessed socket or knuckle 4 supporting a pin 5. Pivotally mounted in the socket 4 on

said pin 5 is one coiled end 6 of a flexible bowed metal or flat spring handle 7 having rigidly secured on the under or inner peripheral face thereof a bowed or segment shaped tapered shoe or liner 8 which reinforces the middle arched portion of said bowed handle 7. The other end of the bowed metal handle 7 is coiled to form a latch head 9.

Integrally formed on the opposite end of 105 the connecting bar 1 is a second split clamping sleeve 10, the split ends of which terminate in integral apertured clamping flanges 11. Integrally formed on the clamping sleeve 10 is a socket or knuckle 12 having one 110

side wall thereof provided with a curved notch or pocket 13 leading into a lower or primary recess 14 which communicates with a smaller and upper latching recess or pocket 15. To use the handle mechanism the clamping sleeves 2 and 10 are adapted to be engaged over the covered rod or bar of a vestibule curtain and there clamped in place by means of bolts or other suitable means engaged through the apertures in the respective flanges 3 and 11 of said sleeves. The open handle 7 is now adapted to be swung downwardly about the pivot pin 5 from the open position shown in Figure 1 into the closed position shown in Figure 3 with the coiled handle head or latch 9 engaged through the side recess 13 to seat in the lower pocket or recess 14 in the socket or knuckle 12. The handle is now adapted to be tensioned and pulled upwardly to permit the coiled handle head 9 to slide upwardly and move from the lower notch 14 into the upper recess or notch 15 and remain seated therein a releasable latched position with the bowed handle 7 under tension in the arched position illustrated in Figure 2 ready for use.

The improved handle mechanism is adapted, as hereinbefore stated, to be mounted on the free end of a vestibule curtain to permit the curtain to be pulled or extended from one car across a vestibule passage to permit the middle reinforced portion of the handle 7 to be engaged on a hook mounted on an adjacent railway car vestibule face plate. Under ordinary conditions of operation the latching end of the handle 7 is adapted to be resiliently held in locked position seated in the recess or pocket 15 of the handle supporting section. When, however, the handle 7 is subjected to abnormal tensile strains as for instance when two railway cars are being separated and an attendant has failed to unhook the curtain, said handle 7 will stand additional tensioning sufficient to permit the latch head 9 of the handle to be pulled or snapped out of the latching recess or pocket 15, thereby automatically releasing the handle 7 permitting the same to swing outwardly about its pivot pin 5 into the position shown in Figure 1 thereby automatically becoming released from engagement with the curtain retaining hook mounted on one of said rail-way cars. This releasing action of the improved handle prevents the destruction of the handle and the curtain on which the handle is mounted thereby obviating the replacement of said handle, saving the expense incidental to the supplying of a new handle if the same was of the old type construction and a curtain was not released prior to the separating of a pair of coaches.

While the improved releasable handle has been described for use in combination with

a railway car vestibule curtain it will, of course, be understood that said handle may be used in any other combination or for any other purpose desired.

I am aware that many changes may be made and numerous details of construction may be varied through a wide range without departing from the principle of this invention and I, therefore, do not purpose limiting the patent granted hereon, otherwise than necessitated by the prior art.

I claim as my invention:

1. The combination with a curtain, of a handle mechanism mounted thereon and comprising a base section, a spring handle section pivotally mounted on said base section with one end of said handle section resiliently latched in said base section for use under normal operating conditions and releasable under abnormal operating conditions when said handle section is subjected to abnormal tensile strains.

2. The combination with a curtain, of a base section secured thereon having a plurality of connected latching recesses therein, a bowed handle section having one end thereof pivotally mounted on said base section, and a head formed on the other end of said handle section adapted to be engaged in one of said recesses and then pulled into latching engagement with the other of said recesses when said handle section is tensioned.

3. The combination with a vestibule curtain, of a handle mechanism secured thereto and comprising a base section having a plurality of latching recesses in one end thereof, a bowed handle pivotally mounted on the other end of said base section, and a latch head on said bowed handle adapted to be swung downwardly for engagement in one of said recesses and then pulled outwardly into spring latching engagement with another of said recesses to hold the bowed handle in a strained latched position for use under normal operating conditions and releasable when subjected to abnormal tensile strains.

4. A handle mechanism comprising a connecting bar, a clamping head on one end thereof, a bowed handle pivotally mounted on said clamping head, a latching head formed on the other end of said handle, a second clamping head formed on the other end of said connecting bar and having latching recesses therein adapted to removably receive the handle latch head engaged therein to hold the handle tensioned and latched under normal operating conditions and permitting release of said handle under abnormal operating conditions.

5. A handle mechanism comprising a base section having latching recesses in one end thereof, a bowed handle pivotally mounted on the other end thereof, a reinforcing seg-

ment secured to said handle, and a latch head on said handle for removable engagement in said latching recesses.

6. A handle mechanism of the class described, comprising a mounting section having a pair of connected latching recesses in one end thereof, a bowed resilient spring handle pivoted in the other end thereof, means for reinforcing said handle, and a resilient latching head formed on said handle adapted to first be engaged in one of said recesses and then pulled into latching engagement with the other of said recesses holding the handle in a bowed tensioned position for use under normal conditions

and permitting automatic release of said handle when subjected to abnormal tensional strains.

7. A handle mechanism of the class described, comprising a notched base section, a resilient bowed handle pivotally mounted thereon adapted to have a resilient latching connection with said base section under normal conditions and further adapted to be automatically released from latching engagement with said base section when the handle is subjected to abnormal strains.

In testimony whereof I have hereunto subscribed my name.

HARRY H. SCHROYER.
